UNITED STATES PATENT OFFICE

ADOLPH W. JENCZEWSKY, OF CHICAGO, ILLINOIS.

SAFETY-VALVE FOR GAS-PIPES.

No. 824,935.

Specification of Letters Patent.

Patented July 3, 1906.

Application filed July 3, 1905. Serial No. 268,146.

To all whom it may concern:

Be it known that I, ADOLPH W. JENCZEWSKY, a citizen of the United States, and a resident of Chicago, in the county of Cook and State of Illinois, have invented certain new and useful Improvements in Safety-Valves for Gas-Pipes; and I do hereby declare that the following is a full, clear, and exact description thereof, reference being had to the accompanying drawings, and to the letters of reference marked thereon, which form a part of this specification.

This invention relates to an electrically-actuated safety-valve intended to be applied to a supply-pipe for illuminating-gas at a point within a house or building for closing the pipe against the passage of gas from the main in case a fire occurs within said house or building and which is adapted for operation from a point distant from the valve.

My invention consists in the matters hereinafter described, and pointed out in the appended claims.

In carrying my invention into practice I provide the gas-supply pipe within the cellar or basement of the building, between the gas-meter and the point where the pipe enters the building, with a valve having a movable part or closure which has a tendency to assume a closed position, together with means for holding the valve normally in its open position, embracing a supporting member or element which constitutes part of an electric circuit and which is adapted to be heated when the circuit is closed therethrough to effect the release of the closure, said circuit being normally open, but adapted to be closed by the use of a switch located at an easily-accessible place within the building or outside of the building and which may be closed in case of fire within the building.

While an apparatus embracing the main or broad features of my invention may be embodied in a construction in which the electric current is employed to release the valve-closure otherwise than by the fusing of the supporting member of the electric current, yet the form of construction embracing such fusible supporting member is preferred, because of simplicity in construction, due to the absence of mechanically-acting parts in the supporting and releasing means. I also prefer a form of construction embracing a supporting member adapted to be fused by an electric current, for the reason that the fusible supporting member itself will be

finally fused in case fire should reach the valve, so that the valve will close automatically in case of fire in the neighborhood of the valve whether the electric releasing device be brought into operation or not.

As illustrated in the accompanying drawings, Figure 1 is a view in central longitudinal section of a valve embodying my invention. Fig. 2 is a horizontal section thereof, taken upon line 2-2 of Fig. 1.

As shown in the said drawings, A indicates a pipe leading from a gas-main, A' a pipe leading to a meter or toward the distributing-pipes of the building, and B a valve-casing which connects the pipes A A'. Said valve-casing B has a transversely-arranged valve-chamber B', one end of which is shaped to constitute a tapered valve-seat. In said valve-seat are formed lateral ports b b', which communicate with the pipes A A'.

C is a valve-plug of conical form, which is movable endwise in the valve-chamber and is adapted to fit within the conical part of said chamber in such manner as to close the ports b b' or to be shifted into the other part of said valve-chamber to effect the opening of said ports. Said valve-plug is so constructed as to have a tendency to assume its closed position either by gravity or otherwise. In the particular construction shown the valve-chamber B' is arranged with its central axis upright and the valve-plug is adapted to be supported in the upper part of said valve-chamber, so that it will tend to fall by gravity to the lower part thereof or to its closed position.

D is a cap which closes the top of the valve-chamber and is preferably connected with the valve-casing by screw-threaded connection.

D' is a screw-cap which closes the lower end of the valve-chamber.

Supporting means for holding the valve-plug C in its elevated position consists, as shown in the drawings, of a loop c on the upper end of the plug, a link E, which is engaged with the said loop c, and a fuse-wire F, which is provided at its ends with insulated supports and engaged between its ends with the said link E. The supports for the ends of the fuse-wire, as herein shown, consist of two rods G G', which extend through the cap D of the casing and are insulated from the same by means of bushings g g', of insulated material. Said rods G G' are shown as provided at their inner ends with binding-screws

g^2 g^3 , by which the ends of the fuse-wire may be readily clamped to the rod. The outer ends of the rods are also provided with binding-screws g^4 g^5 , by which conducting-wires may be connected with said rods. Said binding-screws g^4 g^5 are shown as provided with disk-shaped heads provided each with two holes for a wrench having two pins. This construction prevents any turning of the binding-screws by the fingers and requires a special tool for operating the same, thus preventing unauthorized tampering with the electric connections.

The wires H H', rods G G', and the fuse-wire F constitute parts of an electric circuit. Current for such circuit may be supplied by any suitable generator—as, for instance, by batteries I I'. The circuit will include a switch for closing the same, as indicated in the drawings, by a key J, which stands normally open. The switch or key may be located at any easily-accessible point—as, for instance, in a box at the exterior of the building, which may be opened by firemen for the purpose of closing the switch and releasing the valve-closure.

The valve constructed as described will not only be adapted for the release of the closure and closing of the valve through the fusing of the fuse-wire F by an electric current, but also automatically by the presence of the heat in the immediate neighborhood of the valve. It follows that in case the valve-casing be subjected to a high degree of heat, as from a fire in its immediate neighborhood, the fuse-wire will melt and the valve-closure assume its closed position if there should be no person present to operate the switch in the electric circuit or should the electric circuit be broken or out of order.

To further insure the prompt closing of the valve in case of fire in its immediate neighborhood, I prefer to make the supporting-link E of readily-fusible metal, such as lead. Moreover, if the said link be made of fusible metal the wire F, hereinbefore termed the "fuse-wire," need not necessarily be of such character as to be actually fused or melted by the current passing therethrough, but need only be raised to such temperature as to effect the melting of the link, when the closure will be released in the same manner as though the said wire F were itself fused by the current. In other words, the wire F may consist of a wire having such resistance to the passage of a current that it will be heated by the current sufficiently to melt lead or other readily-fusible metal, so that the closing of the circuit of which said wire forms a part will result in the heating of said wire and the fusing of the fusible supporting member engaging the wire. The link E instead of being made of a

fusible metal may be constructed of other material adapted to be weakened or destroyed by heat, such as celluloid.

An advantage gained by the use of an electric releasing device located within the valve-casing in connection with circuit-wires which pass through the wall of the valve-casing is that the said valve-casing may be permanently closed, and thus rendered safe against the leakage of gas.

I claim as my invention—

1. A safety-valve for gas-pipes comprising a valve-casing, a movable valve-closure in said casing, means for holding the valve-closure in its open position embracing a supporting member which is destructible by heat, and an electric circuit adapted to generate heat for effecting the destruction of the said supporting member and the release of the closure.

2. A safety-valve for gas-pipes comprising a valve-casing, a movable valve-closure in said casing which has a tendency to assume a closed position, and means for holding said valve-closure in its open position including a wire within the casing which is insulated from the casing and forms part of an electric circuit.

3. A safety-valve for gas-pipes comprising a valve-casing, a movable valve-closure in said casing which has a tendency to assume a closed position, and means for holding said valve-closure in its open position embracing a fusible wire located in the casing and insulated therefrom and forms part of an electric circuit.

4. A safety-valve for gas-pipes comprising a valve-casing, a movable valve-closure in said casing which has a tendency to assume a closed position, and means for holding said valve-closure in its open position embracing a wire located in the casing and forming part of an electric circuit and a link made of material which is destructible by heat and which is engaged with said wire.

5. A safety-valve for gas-pipes comprising a valve-casing, a movable valve-closure in said casing which has a tendency to assume a closed position, and means for holding the valve-closure in its open position embracing a fusible supporting member which forms part of an electric circuit, and a link of fusible metal connecting the said closure with said fusible member.

In testimony that I claim the foregoing as my invention I affix my signature, in presence of two witnesses, this 28th day of June, A. D. 1905.

ADOLPH W. JENCZEWSKY.
